UNITED STATES PATENT OFFICE.

JOHN L. LIALE, OF REDLANDS, CALIFORNIA.

IRONING BOARD.

Application filed May 20, 1920. Serial No. 382,792.

To all whom it may concern:

Be it known that I, JOHN L. LIALE, a citizen of the United States, residing at Redlands, in the county of San Bernardino and State of California, have invented new and useful Improvements in Ironing Boards, of which the following is a specification.

This invention is an ironing board and has for its object the provision of a construction including means for supporting the ironing board and detachably connecting the same to a suitable upright, such as a wall or a table.

Further objects of the invention will be readily understood from the following description of the accompanying drawings, in which—

Figure 1 is a side elevation, partly in section, of a practical embodiment of the invention showing the ironing board attached to a wall bracket.

Fig. 2 is a top plan view of the ironing board.

Fig. 3 is a horizontal section on the lines 25 3—3 of Fig. 1.

Fig. 4 is a side elevation of the ironing board, partly broken away, and showing the same attached to a table.

Fig. 5 is a side elevation of the ironing board in folded inoperative position.

The ironing surface comprises a board 1 of conventional shape, this board having a clamping member 2 mounted at its under side adjacent one end of the board and arranged to be adjusted toward and away from the board whereby the board and the clamping member will form jaws arranged to engage opposite sides of a suitable attaching member. An upright 3 is hinged 40 to the end of the clamping member 2 which is opposite its clamping jaw forming end, this upright being, preferably, adjustable in length and arranged to have the ironing board rest upon its upper end and to be supported upon the floor at its lower end when the ironing board is in operative position so as to form supporting means for the ironing board.

In the specific embodiment of the invention, as illustrated, the clamping member 2 is spaced from the under side of the ironing board by a cross bar 4. The clamping member may be adjusted toward and away from the ironing board by means of bolts 5 extending through the ironing board, the cross bar 4, and the clamping member, these

bolts being provided with suitable nuts 6 and locking nuts 7 for adjusting the clamping member.

The clamping member is shown as comprising two angularly disposed arms 2^a and 2^b converging at the hinged connection with upright 3. This hinged connection may comprise a usual hinge 8, preferably, secured to the upright 3 adjacent its upper end. The upper end of the upright 3 forms a removable rest for the ironing board by being received in a suitable recess 9 formed in the under side of the ironing board.

The means for adjusting the length of upright 3 may include a sleeve 10 received over the lower end of the upright, one side of the inner surface of the sleeve being provided with teeth 11 lengthwise of the sleeve and the adjacent surface of the upright 3 being provided with co-operating teeth 12. Engagement of teeth 11 with teeth 12 is arranged to secure the sleeve 10 in adjusted positions lengthwise of the upright 3.

The means provided for retaining teeth 11 and 12 in engagement and for disengaging said teeth so that the sleeve may be adjusted along the upright may consist of hinging the portion of the wall of sleeve 10 provided with teeth 11 so that said toothed portion of the wall may be swung outwardly for disengaging teeth 11 and 12, as shown in dotted lines in Fig. 1. The hinged connection for the toothed wall of the sleeve may comprise a usual hinge 13. When this hinged wall is swung into engagement with teeth 12 it may be latched in tooth engaging position by means of a spring latch 14 upon the toothed wall arranged to engage a catch 15 upon the stationary portion of the wall of sleeve 10.

The clamping jaws formed by the ironing board and the clamping member 2 may be provided with straight end jaw portions 16 and with cross ribs 17 upon the engaging surfaces of the jaws. When the ironing board is attached to a table, as shown in Fig. 4, the straight jaw portions 16, preferably, engage the edge of the table which is shown at 18, and when the ironing board is secured to a wall attachment the cross ribs 17 of the jaws are, preferably, received in oppositely disposed grooves 19 provided in a supporting ledge 20 which may be secured to a wall 21 of a building as by bolts 22 extending through said ledge into a bracket 23 nailed upon the wall as

by nails 24 extending into the studs 25 of the wall.

The ironing board may be provided upon its upper surface with a usual sleeve board 26 shown as supported upon an upright 27 rotatably mounted upon the ironing board as by a bolt 28 extending through the ironing board and the cross bar 4 and provided with a nut 29. A plurality of rack arms 30 10 may also be provided upon the ironing board, these rack arms being shown as pivoted to the under surface of the ironing board as by the pivot screws 31.

In its operative position the ironing board is clamped to either the ledge 20 or to the edge of a table by means of the clamping member 2, and the upright 3 is swung relative to the clamping member until its upper end is received within the recess 9. The length of the upright is adjusted, as previously described, so that the end of the upright will form a support from the floor for the ironing board. By tightening the bolts 5 the ironing board 20 will be rigidly clamped to whatever attaching support is being employed and the ironing board is thus arranged for use.

When it is desired to remove the ironing board, bolts 5 are loosened so that the board 30 may be removed from its supporting attachment and the upright 3 may then be swung upon hinge 8 until the upright is positioned beneath the clamping member 2 substantially parallel thereto, as shown in Fig. 5. The ironing board in this folded inoperative position may be stored away until it is again desired to use the same.

Various changes may be made without departing from the spirit of the invention 40 as claimed.

What is claimed is:

1. An ironing board having a supporting upright notched along one side, a sliding sleeve engaging said supporting upright,

a portion of said sleeve being notched 45 and hinged for swinging movement out of or into engagement with the notches of said upright, and snap latching means for detachably retaining said hinged notched portion of the sleeve in engagement with the 50 notches of said supporting upright so as to adjustably position the sleeve along the length of said upright.

2. In combination, an ironing board, a supporting sleeve, a supporting upright 55 slidably mounted in the sleeve and engaging the ironing board, a portion of said sleeve being hinged to occupy locking and non-locking positions with respect to said upright, said upright and portion being provided with cooperating teeth for adjustably sustaining the upright, and means for securing said portion in locking position.

3. An adjustable support for ironing boards, comprising a supporting sleeve, a 60 supporting upright, said sleeve and upright being slidably associated with each other, a portion of said sleeve being mounted to occupy locking and non-locking positions with respect to said upright, said upright and portion being provided with co-operating means for adjustably sustaining the upright, and means for securing said portion in locking position.

4. In combination, an ironing board, a 65 supporting sleeve, a supporting upright slidably mounted in the sleeve and engaging the ironing board, a portion of said sleeve being mounted to occupy locking and non-locking positions with respect to said upright, said upright and portion being provided with cooperating means for adjustably sustaining the upright, and means for securing said portion in locking position.

In testimony whereof I have signed my 70 name to this specification.

JOHN L. LIALE.
